(57) **CLAIM**

The ornamental design for a combined loudspeaker and speakerphone, as shown and described.

DESCRIPTION

FIG. 1 is a top perspective view of a combined loudspeaker and speakerphone, showing our new design.

FIG. 2 is a front elevational view thereof.

FIG. 3 is a back elevational view thereof.

FIG. 4 is a bottom plan view thereof; and,

FIG. 5 is a side elevational view thereof.

The broken line portions in the figures illustrate the portions of the design that form no part of the claimed design.

1 Claim, 3 Drawing Sheets
